COMBINATION RULER AND COMPASS

Max Skolnick, New York, N. Y.

Application May 23, 1946, Serial No. 671,769

3 Claims. (Cl. 33—27)

1

The present invention relates to new and useful improvements in drawing instruments, and refers more particularly to a combined ruler and compass.

More specifically, the invention proposes the construction of a compass, the legs of which are straight and bear markings constituting them individually as rulers.

Additionally, the legs of the compass are so joined together that they may be positioned each to constitute a straight extension of the other, and the markings of one leg will be complementary to those of the other so that jointly they constitute a single long ruler.

A further object is that the compass handle may be folded or turned so as to overlie the legs of the compass when not in use, decreasing the over-all length of the instrument and permitting it to be more easily carried in the pocket, the overlying position of the handle further serving to protect it against damage under such conditions.

A still further object is that the handle may serve as a locking and unlocking means for the compass in maintaining or changing the relative angular position of the legs thereof, in combination with a nut and bolt means pivotally connecting the legs together.

Still another object is to provide a compass with sleeves for receiving divider points, a pen, pencil or other stylus means, which sleeves shall be bodily adjustable relative to the compass legs on which they are mounted, and novel means for maintaining the sleeves in their adjusted position.

A general object of the invention is that the above shall be embodied in an instrument which shall be economical to fabricate, pleasing in appearance, and simple in operation.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective front view of an instrument embodying the present invention, shown in closed position.

Fig. 2 is a rear view of the same.

Fig. 3 is a side view of the same.

Fig. 4 is a front elevation of the same, partly broken away and showing the legs extended to form a single long ruler.

Fig. 5 is a front elevation of the instrument in closed position, with an open position shown in broken lines.

Fig. 6 is a section on the line 6—6 of Fig. 5.

Fig. 7 is a section on the line 7—7 of Fig. 5.

Fig. 8 is a perspective view of the combination handle and locking aid of the instrument.

2

Fig. 9 is an exploded view of the joint elements of the instrument.

Fig. 10 is an end elevation of a modified form of the invention.

Fig. 11 is a fragmentary section on the line 11—11 of Fig. 10.

Referring now in detail to the drawings, the ruler compass 20, which will be referred to hereafter as a compass, comprises two legs 21, 22, marked with complementary ruler scales and comprising beveled ruling edges 23, 24. Each leg 21, 22 is substantially rectangular in plan view, as clearly seen from Figs. 2, 4, and 5.

Extending from adjacent end corners of the legs 21, 22 are the circular pivot ears 25, 26 formed with central holes 27, 28, the centers of the holes 27, 28 and ears 25, 26 lying on the intersection of the projected end and inner side lines of their respective legs.

A partially threaded pivot 29 passes through holes 27, 28 to pivotally connect the legs 21, 22 together. A washer 30 overlies ear 26 on pivot 29, and a split washer 31 overlies washer 30, also on pivot 29.

The compass handle 32 comprises a substantially tubular portion 33 and a flat portion 34 formed with a hole 35 extending transversely to the axis of portion 33 and to the plane of portion 34, which may be said to extend radially from hole 35. Portion 34 of handle 32 is mounted on pivot 29 overlying washer 31 and in engagement with lock nut 36, the lower radial surface of the latter engaging the radial surface of portion 34, the two surfaces being in frictional engagement when nut 36 is screwed down tight. When in such condition of engagement, the elongated tubular portion 33 serves as a lever for applying the final tightening force to nut 36 and the initial loosening force when it is desired to unscrew nut 36.

It is notable that, because handle 32 and nut 36 are freely rotatable, relatively to each other, except when in frictional engagement, such tightening and loosening of nut 36 may be effected with handle 32 in any desired position relative to legs 21, 22 as seen from the various figures. For instance, in Figs. 1, 2, and 3, the portion 33 overlies legs 21, 22 in order to decrease the overall length of the instrument and in order not to constitute a projection. The compass as thus

locked is conveniently carried in the pocket without needing any protective case. In Fig. 5, the handle 32 and portion 33 thereof in particular extends in prolongation of legs 21, 22 in operative position in the use of the compass. In Fig. 4, portion 33 overlies leg 22, locking the legs in straight extending position to form one long ruler in which the ruling edges 23, 24 form one continuous straight edge and portion 33 does not project so as to interrupt said straight edge, but

rather performs the desirable function of a han-

dle by which the ruler may be conveniently picked up from the work without having to place the fingers on the work in order to reach under the ruler.

Legs 21, 22 each comprise a stylus sleeve 37 fixed thereto in any convenient manner, the sleeve 37 being tubular and comprising a transversely extending screw 38 or other means for the adjustable positioning of divider points 39, pen, pencil 40 or other form of stylus or inscribing means.

Figs. 10 and 11 show a modified form of my invention in which a stylus sleeve 50 with stylus holding screw 51 is adjustable longitudinally of leg 52 of a compass, not shown in entirety. Fig. 10 is an elevation of the writing or inscribing end of the compass leg 52, which end appears at the lower end of Fig. 11.

Leg 52 is formed with a longitudinal opening 53, one side wall of which is formed with ratchet teeth 54, the other side wall 55 being smooth. Opening 53 has top wall portions 56 and 57, and a top slot 58.

Sleeve 50 is mounted on sleeve base 59, extending upward therefrom through slot 58, the sleeve 50 and base 59 being slidable as a unit longitudinally of opening 53 and leg 52. Base 59 is formed with ratchet teeth 60 interengaging teeth 54 and underlying upper wall portion 56. On the opposite side of base 59 from teeth 60 are two lugs 61 extending laterally therefrom and underlying top wall portion 57.

Longitudinally confined by lugs 61 and laterally compressed by base 59 and wall 55 is the leaf spring 62 which tends to keep the teeth 54, 60 in engagement thus longitudinally positioning sleeve 50 on leg 52. It is evident however that by a pressure from left to right of Figs. 10 and 11, bearing on sleeve 50 and conveniently exerted by the fingers, teeth 54, 60 may be disengaged against the action of spring 62 and sleeve 50 adjusted longitudinally of leg 52 upon release of the pressure, spring 62 will cause teeth 54, 60 to reengage at the new position, maintaining the same securely.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In an article of the class described, having adjacent legs pivotally connected together at their adjacent ends, said legs being formed with openings extended in from the free ends thereof and slots of a width less than said openings extending from said openings to one side of said legs, a base slidable longitudinally in each of said openings, each of said bases having portions extending through the slots of their respective openings, stylus holding tubes mounted on the extended portions of said bases, ratchet teeth formed on the walls of said openings along one side of said bases, ratchet teeth formed on the edges of said bases adjacent the ratchet teeth of said wall for engaging said ratchet teeth of said wall, and resilient means operating between the edges of said bases opposite the edges formed with said latter mentioned ratchet teeth and the adjacent side walls of said openings urging said bases to maintain said ratchet teeth engaged.

2. In an article of the class described, having adjacent legs pivotally connected together at their adjacent ends, said legs being formed with openings extended in from the free ends thereof and slots of a width less than said openings extending from said openings to one side of said legs, a base slidable longitudinally in each of said openings, each of said bases having portions extending through the slots of their respective openings, stylus holding tubes mounted on the extended portions of said bases, ratchet teeth formed on the walls of said openings along one side of said bases, ratchet teeth formed on the edges of said bases adjacent the ratchet teeth of said wall for engaging said ratchet teeth of said wall, and resilient means operating between the edges of said bases opposite the edges formed with said latter mentioned ratchet teeth and the adjacent side walls of said openings urging said bases to maintain said ratchet teeth engaged, said ratchet teeth being disposed to slide over one another when the bases are moved to move the stylus holding tubes toward the free ends of said legs and to engage and restrain any movement of the bases and the stylus holding tubes carried thereby away from the free ends of said legs.

3. In an article of the class described, having adjacent legs pivotally connected together at their adjacent ends, said legs being formed with openings extended in from the free ends thereof and slots of a width less than said openings extending from said openings to one side of said legs, a base slidable longitudinally in each of said openings, each of said bases having portions extending through the slots of their respective openings, stylus holding tubes mounted on the extended portions of said bases, ratchet teeth formed on the walls of said openings along one side of said bases, ratchet teeth formed on the edges of said bases adjacent the ratchet teeth of said wall for engaging said ratchet teeth of said wall, and resilient means operating between the edges of said bases opposite the edges formed with said latter mentioned ratchet teeth and the adjacent side walls of said openings urging said bases to maintain said ratchet teeth engaged, said resilient means comprising a spaced pair of lugs formed on the edge of each of said bases opposite the edges formed with said latter mentioned ratchet teeth, and leaf springs of a length greater than the spaces between said pairs of lugs, each leaf spring having its ends engaging its respective lugs holding the leaf spring arched with its intermediate portion engaging the wall of its respective opening opposed to its wall, formed with said first mentioned ratchet teeth holding its respective base in a position in which said ratchet teeth will be engaged.
